UNITED STATES PATENT OFFICE

JAMES WILLIAM WHELAN, OF WASHINGTON, DISTRICT OF COLUMBIA

DESIGN FOR A TOY WINDWHEEL

Application filed January 5, 1933. Serial No. 46,743. Term of patent 14 years.

To all whom it may concern:

Be it known that I, JAMES WILLIAM WHELAN, a citizen of the United States, residing in the city of Washington, District of Columbia, have invented a new, original, and ornamental Design for a Toy Windwheel, of which the following is a specification, reference being had to the accompanying drawing, forming a part thereof.

The figure is a perspective view of a toy windwheel, with the supporting element partly broken away for convenience in illustration, showing my new design.

I claim:

The ornamental design for a toy windwheel, as shown.

J. WILLIAM WHELAN.
